LOCK CAP

Charles C. Turner, Los Angeles, Calif.

Application September 2, 1931. Serial No. 560,764

9 Claims. (Cl. 70—90)

My invention relates to a lock cap suitable for gasoline tanks.

In the ordinary gasoline tanks, such as used on automobiles, the cap is generally attached by such cap having a pair of internal projecting fingers which may be inserted through slots in a flange formed on an upward projection of the gasoline tank. The cap may then be given a partial turn, such as a quarter turn, and becomes securely 10 wedged in position. This is usually due to a cam-shaped internal rim on the projecting neck of the tank.

In connection with this type of cap, an object and feature of my invention is the provision of a 15 lock so that when the cap is once attached to the neck of the tank and the lock is turned to the locking position the cap cannot be removed as it cannot be rotated in a direction to disengage the fingers from the cam rim and to bring these 20 in alignment with the slots or notches in the rim.

In this connection a more detailed object and feature of my invention is forming a bolt which may be operated by the lock, which lock may be 25 of different types, the bolt being of such a nature that it may be retracted or thrust outwardly in a somewhat radial direction. The bolt, when retracted, may be brought into alignment with one 30 of the fingers of the cap and may be thus inserted through the notch in the rim of the neck of the tank and may be carried below the low end of the cam-shaped rim, then when the bolt is projected it will engage the high end of the cam to prevent reverse rotation of the cap.

35 In a modification of my invention I use a simpler type of lock with a radially sliding bolt, in which case the bolt is located out of alignment with the fingers of the cap and the fingers of the cap are inserted in a notch between the cams. The cap 40 is then rotated until the fingers engage a stop. Then, to lock the cap the bolt is thrust radially outwardly into the notch between the cams and prevents the reverse rotation.

In a further construction of my invention the 45 cap is screw threaded on the neck at the tank opening and the lock is provided with a shank which supports the bolt in such a position that when the cap is screwed into position the bolt may be extended and prevent unscrewing and, 50 hence, removal of the cap.

My invention is illustrated in connection with the accompanying drawing, in which:

Fig. 1 is a perspective view of my cap applied to the neck of a tank;

55 Fig. 2 is a vertical section on the line 2—2 of

Figs. 1 or 3 in the direction of the arrows, showing the device in the locked position;

Fig. 3 is a horizontal section on the line 3—3 of Fig. 2 in the direction of the arrows, showing the device in the locked position;

Fig. 4 is a vertical section on the line 4—4 of Figs. 2 or 3 in the direction of the arrows;

Fig. 5 is a section on the line 3—3 of Fig. 2 with the cap in the unlocked position;

Fig. 6 is a bottom view of the cap removed 65 from the tank;

Fig. 7 is a horizontal section through the tank neck showing a modified construction of lock cap and tank neck;

Fig. 8 is a vertical section through a further 70 modification showing the cap threaded on the neck of the tank.

In the illustrations, Figs. 1 through 6, a portion of the tank is designated by the numeral 11. This has a neck 12 extending upwardly, such 75 neck having an inwardly extending flange 13, such flange having a downwardly extending cam-shaped rim 14. This rim has a low portion 15 at one side and a high portion 16 at the opposite side. The rims are not a full semi-circle but 80 there are diametrically opposite slots or notches 17 between the low end of one cam rim and the high end of the other cam rim. In the ordinary practice these rims have a depression 18 for engagement with the fingers of the cap. The 85 rim is usually made entirely of metal.

The cap designated generally at 19 is illustrated as having a disk-like section 20, a flange 21 extending downwardly therefrom, a reduced cylindrical section 22 extending upwardly from 90 the inside portion of the disk, and a dome section 23. This dome section has an opening in which is fitted the lock designated generally at 24. An internal disk 25 and a finger tip 26 are secured on the under side of the domed part by 95 means of a nut 27 threaded on the exterior part of the lock. The lock is indicated as having a rim 28 engaging the upper part of the dome. This construction holds the lock in place and, in addition, the strap is provided with a 100 pair of fingers 29 extending outwardly, which fingers have finger tips 31 to extend underneath the rim of the tank neck, which rim, it will be observed, has an outwardly turned section 32 in which the depressions 18 are formed.

105 In the construction of Figs. 1 through 6, the lock is illustrated of the barrel type having a rotatable barrel 33 operated by a key 34. This barrel in its rotation operates the bolt 35, which bolt has an upper section 36 secured in place by 110

a plate 37, this latter having securing screws 38 fastening the bolt to the bottom of the barrel of the lock. The barrel is eccentric in the lock. The bolt has a downwardly extending section 39 and a projecting operating end 40. The operating end 40, when retracted, has its tip of substantially the same radius as the tips 31 of the fingers 29, and when the cap is unlocked may be inserted through the notches 17. However, the tip portion 41 extends downwardly below the finger tips to such an extent that it will clear the low part of the cam on the rim of the neck of the tank but not below the high portion of such cam.

15 The manner of operation of this modification of the lock is as follows:

The cap is unlocked with its bolt in the position shown in Fig. 6, in which it will be seen that the bolt and the fingers which are rigidly secured to the cap are in alignment. The cap is then inserted on the tank with the bolt and the fingers passing through the notches 17. The cap is then rotated, which brings the fingers into registry with the depression 18 of the cams, preventing further movement of the cap and securely holding this in position and pressing the packing 42 against the flange 13 of the neck of the tank. In this turning movement of the cap, the lock and the retracted bolt is turned with the cap. Then, on operating the key the bolt is turned in a reverse direction to that of the cap in securing to the neck and brings the bolt into the position shown in Fig. 3, in which it is thrust outwardly radially but it is in vertical alignment with one of the notches 17. This brings one side of the bolt close to the end 43 of the high side of one of the cams on the rim of the neck of the tank. Therefore, it is impossible to rotate the tank cap in the counter clockwise direction of the arrow 44 of Fig. 3 to disengage the fingers from the notches 18 and thus from the cams to bring these into alignment with the notches 17 for removal of the cap. Hence, the cap is firmly locked to the neck of the tank.

45 In Fig. 7 I have illustrated a modification in which the cam rim 45 of the neck of the tank has the out-turned portions 46, each of which is provided with a depending stop abutment 47. The cap is constructed in the same manner as above described, as far as the fingers are concerned, these fingers being insertable through opposite notches 17, but the fingers can only be turned until they come into engagement with a stop 47, this being illustrated as substantially a 45 degree turn, whereas in Figs. 3 and 5 the fingers are illustrated as having a 90 degree turn. This construction is adapted for a simpler type of lock which has a sliding bolt 48 operating in guides 49 and manipulated by a lock construction operated by a key. This bolt is radially slid able and may be retracted inside of the rim of the neck of the tank. In applying this type of cap to a tank, the bolt is retracted, permitting the fingers which are securely attached to the cap to be inserted through the notches 17 between the complementary cams. The cap is then rotated until the fingers engage the stops 47, this preventing further movement. The key then operates the lock to throw the bolt radially outwardly into one of the notches 17, as indicated in Fig. 7, and hence, as the high side 16 and the end edge 43 of the cam are adjacent the bolt, the cap cannot be rotated in a reverse direction to that of the arrow 50 to disengage the cap.

It will be obvious that different types of locks may be utilized with my invention.

In Fig. 8 the tank is illustrated as having a neck 51 screw threaded on the outside with a turned-in flange 52, and the cap 53 is indicated as having a threaded skirt 54 threaded on the neck 51. The lock 55 has a stem 56 projecting inwardly in the cap and carrying the bolt 57. This bolt may be retracted in order to clear the opening in the flange 52 and may be held retracted while the cap is being screw threaded into position. When the cap is finally located attached sufficiently to the neck, the key in the lock may be operated to extend the bolt so that it will engage on the inside of the tank adjacent the neck as indicated at 58. This will prevent unscrewing of the cap.

Various changes may be made in the details of construction without departing from the spirit or scope of the invention as defined by the appended claims.

I claim:

1. In a device as described, having a tank with a filling opening and an upstanding neck, an inwardly extending rim formed in two cam-shaped parts separated by a pair of diametrically opposite notches, each part having a slope from a low to a high end, a cap fitting on the neck and having a pair of depending and laterally extending fingers, said fingers being insertable through said notches and rotatable with the cap to engage the cam, means to form a stop position in the rotation of the cap combined with a lock having a bolt, said bolt being extensible and retractable, and in an extended position being in alignment with one of the notches, said bolt being positioned to clear the low end but to engage the high end of the cam and prevent the reverse rotation of the cap to prevent removal.

2. In a device as claimed in claim 1, said bolt in its retracted position being in alignment with one of the fingers and being insertable through one of the notches, said bolt being rotatable with the cap when turning the cap to its securing position and having a reverse motion on locking to return the bolt into alignment with the notch through which it enters the neck of the tank.

3. In a device as described, a tank having a filling opening with a neck, an internal rim formed in two cam-shaped parts spaced by two diametrically opposite notches, each part having a low and a high end, such ends being adjacent the notches, a cap having a pair of diametrically extending fingers insertable through the notches, the cap being rotatable, at least one of the parts of the rims having a stop to engage the finger combined with a lock in the cap having a slide able bolt, said bolt when the cap is in its secured position being in alignment with one of the notches, and in its retracted position being clear of the rim, and in its projected position extending into alignment with a notch to engage the high end of one of the cams and thereby prevent reverse rotation of the cap.

4. In a device as described, having a tank with a filling opening and an outstanding neck, an inwardly extending rim with a pair of vertical notches therein and a stop means on the rim, a cap fitting on the neck and having a pair of depending laterally extending fingers, said fingers being insertable through said notches and rotatable with the cap to engage the stops, a lock on the cap having a bolt, the bolt when retracted being insertable with one of the fingers through one of the notches, and when the cap is turned

with the fingers engaging the stop the bolt may be projected to engage the rim at one of the notches and prevent reverse rotation of the cap.

5. In a device as described, having a tank with a filling opening and an upstanding neck with an inwardly extending rim having two cam-shaped parts separated by a pair of vertical notches, each part of the cam sloping from a low to a high end, a cap having a lock with a pair of fixed fingers secured to the cap by the lock, said fingers being insertable through the notches and rotatable with the cap until they contact with the under surface of the cams, the lock having a bolt mounted to swing in the arc of a circle, said bolt in its retracted position being in alignment with one of the fingers and insertable in one of the notches, and when the cap is rotated to bring the fingers into engagement with the cams, said bolt when projected engaging the high side of one 20 of the cams at one of the notches and preventing reverse rotation of the cap.

6. In a device as described in claim 5, the cams having stop devices to limit the rotation of the cap relative to the neck and cams.

25 7. In a device as described, a cap for a filler opening for a tank, said cap having a disk-like section over the opening and a flange to engage the neck of the opening, a lock having a lock housing extending through the disk portion, said lock housing being threaded externally, a nut threaded thereon, a pair of fixed fingers secured on the lock housing by the nut, said lock having a rotatable barrel with a bolt actuated thereby, the tank opening having a neck with an inwardly and downwardly turned rim with a pair of diametrically opposite notches, the rim having a pair 35 of stop devices to engage the fingers on rotation of the cap after inserting the fingers through

the notches, the bolt being movable in the arc of a circle and in its retracted position being in alignment with one of the fingers and in its projected position after the fingers have been rotated said bolt being in alignment with one of the notches and engaging the side of the notch to prevent reverse rotation of the cap.

5. In a locking device of the class described, the combination with a gasoline tank filling spout having an inwardly extending annular flange provided with a notched portion therein, a rotary cap adapted to fit over said spout, a lock barrel with rotating post, an arm carried by said cap and adapted to be brought into and out of engagement with said flange by the rotary movement of the cap, a finger carried by said post and movable therewith and adapted to be brought into and out of alignment with said arm and also into engagement with the side of said notched portion.

8. In a locking device of the class described, the combination with a gasoline tank filling spout having an inwardly extending annular flange provided with a notched portion therein, a rotary cap adapted to fit over said spout, a lock mechanism carried by said cap, said mechanism comprising a barrel with a rotating post therein, means for controlling the movement thereof, an arm carried by said cap and fitted to pass through said notched portion and adapted to be rotated with the cap and brought beneath the flange and to engage the same, a finger carried by said post, means for moving said finger in alignment with said arm, and means for moving it independently of said arm and into engagement with the side of said notched portion.
